VARIANT-HEIGHT-LOOP TERRY FABRIC
Marvin A. Law, Leaksville, N.C., assignor to Fieldcrest
Mills, Inc., Spray, N.C., a corporation of Delaware
Filed Apr. 16, 1959, Ser. No. 806,826
15 Claims. (Cl. 139—396)

This invention relates to a novel terry fabric and method of making the same, which fabric may be in the form of closely woven piles to form towels, wash cloths, floor mats and the like or in the form of substantially spaced piles forming so-called chenille fabrics, such as bedspreads, drapery cloth, upholstery and the like. This application is a continuation-in-part of my copending application Serial Number 791,716, filed February 6, 1959 and entitled Method and Apparatus for Weaving Variant-Height-Loop Terry Fabrics.

The manufacture of rug and carpet fabrics on looms utilizing variant-height pile wires, and reeds which beat-up to the same position with each stroke thereof for producing randomly positioned loops of many different heights on the base fabric, is well established in the art. However, randomly positioned, variant-height-terry loops cannot be produced by means of pile wires on a terry loom, because the weaving of terry fabrics involves the use of relatively tight ground warps and relatively loose terry warps with a variable beat-up mechanism for the reed of the loom. The variable beat-up mechanism is operable at certain intervals to advance terry warps relative to the ground warps, in a so-called fast pick, to bunch up the terry warps at the fell of the cloth to form a row of loops in front of the reed throughout the width of the fabric at those points where terry warps are present.

For many years, terry looms have been capable of forming piles of one height in any given weftwise row, or the terry warps were not overfed at certain intervals so they were merely woven into the base fabric. Various attachments have been constructed for varying the height of certain weftwise rows of terry piles, but all the piles in each weftwise row were still of the same height. It is also common practice to weave terry fabrics having piles on both sides. However, in instances in which a solid pattern was to be formed on one side of the fabric, the pattern on the other side may also be solid, but the patterns on both sides of the fabric would have to extend, of uniform height, throughout the width of the fabric or certain areas were entirely devoid of loops.

It is an object of this invention to provide an improved terry fabric and method of making the same, which fabric is provided with terry loops or piles which vary in height in certain selected longitudinal or warpwise rows and which also vary in height in certain selected weftwise rows which intersect said warpwise rows.

It is still another object of this invention to provide an improved terry fabric and method of making the same in which either or both faces of the terry fabric are provided with randomly positioned loops of two or more different heights.

It is still another object of this invention to provide a method and fabric of the character described in which some or all of the loops are cut to form tufts.

Some of the objects of the invention having been stated, other objects will appear as the description proceeds when taken in connection with the accompanying drawings, in which—

FIGURE 1 is an isometric view of one form of the improved terry fabric showing different heights of terry loops somewhat schematically;

FIGURE 2 is a vertical sectional view looking warpwise of the fabric and being taken substantially along line 2—2 in FIGURE 1;

2

FIGURE 3 is another form of terry fabric embodying the present invention;

FIGURE 4 is a weftwise sectional view taken substantially along line 4—4 in FIGURE 3;

5 FIGURE 5 is a view similar to FIGURES 1 and 2, but showing still another form of terry fabric embodying variant-height loop formations according to the present invention;

10 FIGURE 6 is a weftwise sectional view taken substantially along line 6—6 in FIGURE 5;

FIGURE 7 is a diagrammatic view showing examples of many different heights of terry loops which may be combined in any desired manner, with the weftwise rows thereof being shown in perspective;

15 FIGURE 8 is a somewhat schematic isometric view of a piece of fabric having variant-height loops appearing on opposite faces thereof;

20 FIGURE 9 is a plan view of a piece of fabric embodying a typical design arrangement which may be produced in a towel, for example, in practicing the present invention;

FIGURE 10 is a schematic elevation, partially in section, showing essential characteristics of a loom, such as that disclosed in said copending application, for producing fabric according to the present invention;

25 FIGURE 11 is an isometric view of a piece of fabric having piles originally woven as loops of two heights with the high loops being sheared.

The various forms of terry fabrics disclosed herein 30 are illustrative of only a few of many different fabrics which may be made according to the basic principles of the present invention. While all the forms of fabric disclosed herein differ in some respects, they are all constructed according to the basic principle of this method, 35 which includes relatively varying the amount of terry yarn in each of certain weftwise rows of loops and successively, relatively varying the amount of yarn in forming successive loops from each of certain of the terry yarns.

Accordingly, in order that the loop formations on the 40 various fabrics disclosed herein may be clearly understood, the parts of the loom disclosed in FIGURE 10 will now be described. In order to simplify the description, many of the parts of the loom are omitted in FIGURE 10. However, reference is made to my copending application, Serial Number 791,716, for a more detailed description of the loom.

In FIGURE 10, fabric F is woven from tensioned ground warps W and terry warps T. The ground warps W are drawn from a warp beam 10 over a roll 11 and then forwardly through heddles or harnesses, of which four are shown indicated at 12 through 15. Ground warps W then pass forwardly through a reed 16 carried by an oscillating lay 17. Reed 16 beats up weft yarns, not shown in FIGURE 10, to form the fabric F. The 55 reed 16 is of a type which moves back and forth with a given range of movement during the weaving of plain fabric and which is periodically shifted rearwardly and then forwardly relatively to the lay 17 to form so-called respective loose and fast picks. The means for shifting reed 16 relative to lay 17 is commonly known as a variable beat-up mechanism which operates in conjunction with a terry-warp-overfeed mechanism generally designated at 20.

Overfeed mechanism 20 comprises a pair of intermittently driven let-off or feed rolls 21, 22. The terry warps T pass downwardly from a terry warp beam 23 beneath the feed roll 21, then between feed rolls 21, 22 and over and downwardly from feed roll 22. Feed rolls 21, 22 may be driven by any suitable means to intermittently draw terry warps T from beam 23 predetermined amounts. The means for driving rolls 21, 22 and imparting varying amounts of rotative movement thereto

in timed relation to operation of the variable beat-up mechanism embodied in the reed 16 may be substantially as is disclosed in my said copending application.

The terry warps pass downwardly from feed roll 22 and beneath an idler roll 24, from whence they pass forwardly through certain of the heddles 12-15 and, thence, to the reed 16. It will be noted that, as terry warps T leave feed roll 22, they are split into a plurality of sheets; i.e., three in this instance, indicated at S, S' and S" (FIGURE 10). Each sheet of terry warps S, S', S" may include individually spaced yarns or spaced groups of yarns alternating with individual yarns or with groups of yarns in the other sheets. Of course, any one of the sheets may include a single group of yarns disposed in offset relation with respect to groups of yarn in the other sheets.

The two sheets S, S' are maintained separate between feed roll 22 and lateral guide or idler roll 24 by a laterally extending slackening bar 31 supported in eccentric relation to a rock shaft 32 by means of rocker arms 33, only one of which is shown. By means not shown in the present application but being fully disclosed in said copending application, the slackening bar 31 is oscillated backward and forward predetermined amounts in timed relation to operation of the overfeed mechanism 20 and variable beat-up mechanism 16. In this instance, the third sheet of terry warps S" is maintained intact; i.e., out of engagement with the first and second sheets, S, S' to permit the same to be slackened or fed with the sheets S, S', by means of an additional lateral guide or idler roll 35. It will be noted that sheet S" passes downwardly and rearwardly, at an angle, from feed roll 22, partially around roll 35, and then forwardly beneath idler roll 35. The three sheets S, S', S" are thus gathered into a single sheet at idler roll 24, where all three sheets are advanced to the reed 16.

From the foregoing, it is apparent that feed roll 21 draws a given length of terry warps T from beam 23 with each intermittent rotational movement thereof. If slackening bar 31 remains stationary between the time that feed rolls 21, 22 are operated and the next succeeding beat-up stroke of lay 16 in the forming of a fast pick, all three sheets of terry warps S, S', S" will have been slackened equal amounts and all terry loops formed therefrom with the next fast pick will be of the same height throughout the width of the fabric F. At this instant, feed rolls 21, 22 may move a normal, medium, amount; or they may move a reduced or substantially increased amount; depending upon whether loops of medium, relative short or relatively long length are to be formed in the respective weftwise row.

However, as disclosed in said copending application, slackening bar 31 is alternately moved forwardly and rearwardly at certain predetermined intervals and for certain predetermined distances. Thus, depending upon the length of stroke imparted to slackening bar 31, as slackening bar 31 moves away from either sheet S, S', the amount of slack in this sheet is increased. Also with movement of slackening bar 31 away from the latter sheet and into engagement with the other sheet, some or all of the slack in the other sheet may be removed. It follows, therefore, that the immediately succeeding active or beat-up stroke of lay 17 will form loops of intermediate height from those yarns in medium sheet S", relatively long loops will be formed from those yarns in the transpositional sheet which was additionally slackened by movement of the slackening bar 31 away from the same, and relatively short loops, or no loops at all (ground-engaging loops), may be formed from the yarns in the transpositional sheet which was tightened by slackening bar 31. Accordingly, sheets S, S' may be termed as "transpositional sheets" or "transpositionally tensioned sheets," and sheet S" may be termed as an "intact" or "medium tensioned sheet."

Let us assume, for example, that slackening bar 31 occupies the position shown in FIGURE 10 and reed 16 has moved to the broken line position relative to lay 17 for inserting so-called loose picks. After a final loose pick is inserted, feed rolls 21, 22 operate to feed a predetermined amount of terry warps T. This produces a certain amount of slack in the sheets of terry warps S, S', S". If slackening bar 31 remains stationary, the subsequent fast pick stroke of reed 16 produces loops of a medium height or length from all of the terry warps.

If slackening bar 31 moves from left to right in FIGURE 10, away from sheet S' and into engagement with sheet S, with the next fast pick beat-up stroke of reed 16, medium height loops would be formed from those terry warps in sheet S", relatively long loops would be formed from those terry warps in transpositional sheet S' and relatively short loops would be formed from those terry warps in transpositional sheet S. Of course, the extent of movement of slackening bar 31 away from sheet S' and toward sheet S would determine how much additional slack would be effected in sheet S' and how much slack would be removed from sheet S. The slackening bar 31 need not move all the way out of engagement with the terry warps in sheet S' and need only barely press against sheet S so that the heights of loops formed from the terry warps in the sheets S, S' would be relatively slight as shown in the right-hand portion of FIGURE 7.

With a relatively long stroke of slackening bar 31, extra long loops would be formed from the terry warps in sheet S' and extra short or ground-engaging loops would be formed from the terry warps in the sheet S. The reverse movement of the slackening bar 31; that is, from right to left in FIGURE 10 would also have a similar effect on the size of loops formed, but in opposition to the effect produced in the sheets S, S' when slackening bar 31 moves from left to right. In all instances, regardless of the extent of movement of slackening bar 31, those loops formed from terry warps in sheet S" will be of the same height. However, in instances in which the amount of movement of feed rolls 21, 22 is varied, it is apparent that corresponding variations will take place in the length of all of the loops formed from all three sheets of terry warps S, S', S".

From the foregoing description, the manner in which the various loops are formed in the different forms of fabric disclosed herein may be readily understood.

In FIGURES 7 and 8, various combinations of different height loop formations are shown. A particular fabric may or may not include the specific combinations of loops shown in FIGURES 7 and 8. However, these views are provided to illustrate many of the loop height combinations which may be produced according to the present invention. The base or ground fabric in FIGURE 7 is indicated at F1, the warpwise rows of loops are indicated at T1, T2, T3, T4 and T5, and the weftwise rows of loops are indicated at 41 through 64. For purposes of clarity, only a relatively narrow portion of fabric is shown, and since the terry warps are continuous throughout the length of the fabric, it is apparent that the portions of terry warps connecting adjacent warpwise loops are omitted in both FIGURES 7 and 8. The terry warps may be the same size as the ground warps and wefts, or they may be relatively large, soft, yarns; twisted or untwisted, as illustrated.

By way of example, the loops in warpwise rows T1, T4 may be formed from the terry warps in transpositional sheet S of FIGURE 10; the loops in warpwise row T2 may be formed of terry warps in transpositional sheet S' and the loops in warpwise rows T3, T5 are formed from the terry warps in medium sheet S" of FIGURE 10. In forming weftwise row 41 of FIGURE 7, slackening bar 31 (FIGURE 10) occupies a position against sheet S as terry warps T are fed medium amounts by variable overfeed mechanism 20, and slackening bar 31 moves, in a medium stroke, from right to left to substantially the

position shown in FIGURE 10 before, or at the same time as, reed 16 moves forwardly in a fast beat-up stroke. Accordingly, high loops H are formed in warpwise rows T1, T4 from the terry warps in sheet S; low loops L' are formed from respective terry warps in sheet S'; and medium height loops M'' are formed in rows such as T3, T5 from the terry warps in sheet S''.

In forming the next succeeding weftwise row 42, slackening bar 31 remains stationary so that medium height loops M, M', M'' (all of the same height) are formed in all rows T1 through T5 from terry warps in the respective sheets S, S', S''. Since slackening bar 31 is stationary when weftwise row 42 is formed, overfeed mechanism may or may not feed a greater or lesser amount of terry warps T. Thus, loops M, M', M'' in row 42 may or may not be of greater or lesser height than adjacent so-called high and low loops H, H', L, L'.

Now, in forming weftwise row 43, slackening bar 31 moves in the reverse direction, in a medium length stroke, so that low loops L are formed from terry warps in sheet S and in respective warpwise rows T1, T4; high loops H' are formed in warpwise row T2 and any corresponding rows, not shown, from terry warps in sheet S' and medium height loops M'' are again formed in warpwise rows T3, T5 from terry warps in sheet S''.

In forming the next weftwise row 44, slackening bar 31 again remains stationary so that all the loops in row 44 are of medium height and correspond to the loops in weftwise row 42. Weftwise row 45 is also identical to weftwise row 41.

With respect to the portion of the fabric including weftwise rows 41 through 45, it is apparent that high and low loops are formed in alternating sequence in those warpwise rows T1, T2, T4 whose loops are formed of terry warps in sheets S, S', although any number of medium height loops M, M' may be formed between adjacent high and low loops in any given warpwise row. It should also be noted that the high and low loops in warpwise rows formed from the terry warps in one of the transpositional sheets S, S' (FIGURE 10) are formed in opposite relation to the high and low loops formed of the terry warps in the other of the two transpositional sheets; that is, whenever high loops H are formed from terry warps in sheet S, low loops L' are formed from terry warps in sheet S', and whenever low loops L are formed from warps in sheet S, high loops H' are formed from warps in sheet S'. This is true although selected warpwise rows may include loops of infinitely varying heights.

In forming the weftwise rows of loops 46, 47, 48 in FIGURE 7, medium lengths of terry warp T are fed or let off by feed rolls 21, 22, as is the case in the forming of the loops in weftwise rows 41 through 45. However, the slackening bar 31 has a greater or extra range of movement in forming the loops in weftwise rows 46, 47, 48 than it does in forming loops in rows 41 through 45. It is thus seen that, although the medium loops M2'' in warpwise rows T3, T5 are of the same height in rows 46, 47 and 48 as they are in the preceding rows 41 through 45, the high loops H2, H2' are somewhat higher than the high loops H and the low loops L2, L2' are somewhat lower in weftwise rows 46, 47, 48 than the low loops L, L' in weftwise rows 41, 43, 45. In all other respects, weftwise rows 46, 48 are formed in the same manner as weftwise row 43 and the weftwise row 47 is formed in the same manner as weftwise rows 41, 45.

In forming the rows 49 through 53 in the central portion of FIGURE 7, the range of movement of slackening bar 31 may be medium; that is, it may be the same as it was in the formation of the loops in weftwise rows 41 through 45. However, the overfeed rolls 21, 22 advance the terry warps T to a greater extent in the forming of weftwise rows 49 through 53 than they do in the forming of the preceding rows 41 through 48. It is apparent, therefore, that the high loops H3, H3' in weftwise rows 49 through 52 may be slightly longer or higher than the

high loops H, H', H2, H2' in the preceding weftwise rows 41, 43, 45, 46, 47, 48. Also, the low loops L3, L3' in weftwise rows 49 through 52 may be relatively longer or higher than the low loops L in weftwise row 43 and, as a matter of fact, they may even be as high as the medium length or height loops M, M', M'', M2'' in weftwise rows 41 through 48.

Since the overfeed mechanism 20 feeds a greater amount of terry warps in the forming of weftwise rows 49 through 53 than it does in the forming of weftwise rows 41 through 48, it follows that medium height or length loops M3, M3', M3'' in weftwise rows 49 through 53 are of substantially greater length or height than are the medium height loops in rows 41 through 48. In all other respects, the high and low loops H3, L3' and L3, H3' and the medium loops M3, M3', M3'' in rows 49 through 53 are formed in the same manner as corresponding loops in the respective weftwise rows 41, 43 and 44. Ground-engaging loops G in weftwise rows 54, 63, 64 may be formed by letting off a very small amount of the terry warps through the medium of the overfeed mechanism 20 while slackening bar 31 remains stationary, or these ground-engaging loops may be formed by merely inserting a few loose picks and then inserting a fast pick in the fabric.

In forming the group of weftwise rows 55 through 58, the strokes of the slackening bar 31 may be medium; that is, substantially the same as the strokes of the slackening bar 31 in forming the rows 41 through 45 and 49 through 54. However, the amount of overfeed of the terry warps, effected by the overfeeding mechanism 20, is reduced as compared to the amount fed in the forming of each of the rows 41 through 53. The slackening bar 31 remains stationary in the forming of row 55 and, therefore, all of the loops M4, M4' and M4'' in weftwise row 55 are of the same height, but are of lesser height than the medium height loops formed in any of the preceding weftwise rows 41 through 53. Further, it will be noted that all of the loops M4'' appearing in those portions of warpwise rows T3, T5, which correspond to weftwise rows 56 through 58 are of the same medium height.

Weftwise row 58 is formed in the same manner as weftwise row 55. Since the slack bar 31 moves in a medium stroke in each direction in the forming of rows 56, 57, and the amount of terry warps T fed by the overfeed mechanism 20 is relatively reduced, it should be noted that the high loops H4 and H4' in the respective rows 56, 57 are relatively shorter than the high loops H, H' in the respective rows 41 through 43, for example.

Also, low loops L4, L4' in the respective weftwise rows 57, 56 are relatively shorter than low loops L, L' in the respective weftwise rows 43, 41, for example. It will be noted that the low loops L4, L4' in weftwise rows 57, 56 are substantially the same size as the ground-engaging loops in row 54. While the loops L4, L4' may be of substantially greater height than the ground-engaging loops G, they are shown at the same height as the ground-engaging loops G in order to point up the fact that ground-engaging loops can be provided in alternation with high loops in any given warpwise row, and in opposition to ground-engaging loops and high loops in certain other warpwise rows, in producing certain patterns.

In forming the weftwise rows of loops 59 through 62, medium amounts of terry warps T are fed by the overfeeding mechanism 20, but the extent of movement of slackening bar 31 (FIGURE 10) is relatively reduced. This results in high loops H5, H5' being formed in weftwise rows 59, 60 which are substantially the same height as, or slightly lower than, high loops H, H' in respective weftwise rows 41, 43. Since slackening bar 31 then moves only a relatively small amount in each direction in FIGURE 10, it is apparent that slackening bar 31 may actually remain in engagement with that sheet of transpositional terry strands S or S' away from which it is last moved so that the heights of the high loops H5, H5' and low loops L5, L5' is relatively slight. In other words, the low loops

L₅, L_{5'} are substantially higher than the low loops **L, L'** in respective rows **41, 43**, for example. Also, it will be noted that the medium height loops **M₄, M_{4'}, M_{4''}** in weftwise rows **59** through **62** are of substantially the same height as the medium height loops **M, M', M''** in weftwise rows **41** through **48**.

In all other respects, weftwise rows **59, 60** and **61** are formed in substantially the same manner as the respective weftwise rows **41, 43** and **45**. Weftwise row **62** is formed in the same manner as weftwise row **42**. As heretofore stated, the last two weftwise rows **63, 64** are in the form of ground-engaging loops **G** and may be formed in the same manner as weftwise row **54**.

In FIGURE 8, high, low and medium loops are provided, some of which project from one face of a base fabric **F₂** and others of which project from the other face of the base fabric. The warpwise rows are indicated at **T₆, T₇, T₈** and the weftwise rows are indicated at **65** through **75**. Since the portion of fabric shown in FIGURE 8 is illustrated schematically and isometrically, adjacent loops in the various weftwise and warpwise rows of loops are interconnected by dash-dot lines in order that the exact relationship of the various loops may be clearly understood.

Generally, the warpwise rows of loops **T₆, T₇, T₈**, shown in FIGURE 8, may be formed in the same manner as loops in warpwise rows **T₁, T₂, T₃** in FIGURE 7. In other words, the loops in warpwise row **T₆** may be formed from the sheet of terry warp **S**, those loops in warpwise row **T₇** may be formed from terry warps in sheet **S'** and those loops in warpwise row **T₈** may be formed from terry warps in sheet **S''** (FIGURE 10). The primary purpose of the illustration of FIGURE 8 is to point up the fact that various pattern effects can be produced in which loops of one or more sizes may appear in different zones or in opposition on either face of a base fabric.

Reading from left to right in FIGURE 8, it will be noted that those loops in row **T₆** projecting from the upper face of base fabric **F₂** include two high loops **H₆**, then three medium height loops **M₆** and then two low loops **L₆**. Warpwise row **T₇** also includes two high loops **H_{6'}**, three medium height loops **M_{6'}** and two low loops **L_{6'}** in succession, although high loops **H_{6'}** and low loops **L_{6'}** are disposed in warpwise staggered relationship to high loops **H₆** and low loops **L₆**. In warpwise row **T₈**, it will be noted that three medium height loops **M_{6''}** appear on the upper face of base **F₂** in immediate succession and then five more medium height loops **M_{6''}** are spaced to the right of the first-mentioned three medium height loops **M_{6''}**.

Now, since high and low loops are formed in alternation, it will be noted that two low loops **L_{6a}** are formed in row **T₆** to the right of the respective high loops **H₆** and which extend from the lower face of the base fabric **F₂**. A high loop **H_{6a}**, projecting from the lower face of base fabric **F₂** is also formed in advance of each low loop **L₆** projecting from the upper face of the base fabric **F₂**.

In the left-hand portion of warpwise row **T₇** (FIGURE 8), it will be noted that a low loop **L_{6a'}** is provided in advance of each high loop **H_{6'}** and, in the right-hand or upper portion of warpwise row **T₇**, a high loop **H_{6a'}** projects from the lower face of the base fabric **F₂** subsequent to each respective low loop **L_{6'}** projecting from the upper face of the fabric. In warpwise row **T₈**, medium loops **M_{6a''}** project from the lower face of the base fabric **F₂** between the two groups of medium loops **M_{6''}** projecting from the upper face of the base fabric **F₂** in warpwise row **T₈**.

From the description just given with respect to FIGURE 8, it is apparent that many different embossed effects may be produced such as that illustrated in the towel fabric shown in FIGURE 9. Let it be assumed that towel fabric **80** of FIGURE 9 is woven from left to right and opposed sides of the fabric are identical, with

the exception that circular or design areas **81** are raised on the top face of the fabric and are recessed on the opposite face of the fabric. It may then be preferred, but not necessary, that the base **F₂** of the fabric is made from the same or larger size yarns than those forming the pile.

Accordingly, a narrow end edge or header portion **82** may be formed with the terry warps **T** (FIGURE 10) maintained taut along with the ground warps **W**. In other words, the narrow end edge area **82** would be in the form of a flat fabric weave. A transverse border band **83** would then be woven in which the slackening bar **31** of FIGURE 10 would remain stationary and terry warps **T** would be fed constant predetermined amounts by the overfeeding mechanism **20**. Thus, loops formed from alternate yarns may appear on the lower face of the fabric and loops formed from intervening yarns may appear on the upper face of the fabric to form the border band **83**. Thereafter, a narrow recessed transverse margin **84** may be formed by reducing the extent to which the terry warps **T** are fed by the overfeeding mechanism **20** so that relatively low or ground-engaging loops would be formed with alternate and intervening terry warps on opposite faces of the fabric **80**. Of course, the marginal band **84** may be formed by maintaining taut the terry warps **T** so it would be in the form of a flat woven fabric.

After the narrow marginal band **84** is woven in the manner described, the patterned body **85** of the fabric **80** is woven throughout by alternately forming high and low loops, such as loops **H, L** in FIGURE 7 from each alternate yarn and while forming low and high loops, such as loops **L', H'** in FIGURE 7 from each intervening terry warp. It is apparent that manipulation of the heddles **12** through **15** may be such as to cause all low loops to appear on the upper face of the extreme left-hand portion of the patterned body **85** while all high loops will appear on the lower face of the patterned body **85** until the designs **81** in the first row in the left-hand portion of the patterned body **85** are to be woven. At that time, heddles **12** through **15** are so operated as to cause all the relatively long loops formed from the terry warps to appear on the top face of the fabric in those areas indicated at **81** while the remaining portions of the top face of the fabric have relatively low loops appearing thereon. On the other hand, on the opposite face of the fabric **80** from that shown in FIGURE 9, all areas **81** would be formed from low or short loops only and all the remaining portions of the patterned body **85** would be formed from relatively long loops.

The right-hand portion of the patterned area **85** is woven in the same manner as the extreme left-hand portion thereof and, also, the narrow transverse marginal area **84'**, the transverse border area **83'** and the right-hand end edge area **82'** may all be woven in the same manner as the respective areas **84, 83, 82** in the left-hand portion of FIGURE 9.

It is thus seen that all the designs **81** are raised slightly with respect to the surrounding portions of the patterned body **85** on the top face of the fabric so that the designs **81** on the top face of the fabric form embossed effect areas and, on the reverse or bottom face of the fabric **80**, the main portions of the patterned body **85** will include relatively long loops while the design portions **81** include relatively short loops so the areas **81** are recessed with respect to the remaining portions of the patterned body **85** and thus form recessed effect areas on the bottom face of the fabric which complement or coincide with the embossed effect areas on the top face of the fabric. Although the designs **81** are shown in the form of circles, it is apparent that these designs may be of any desired configuration. After the fabric **80** is formed the tops of the high loops at either or both sides may be severed or sheared to produce a smoother fabric having a softer hand and feel, if desired. An example of a portion of

such fabric, with sheared high loops, is shown in FIGURE 11.

In FIGURES 1 through 6 and 11, various other types of fabric are shown which may be woven according to the principles of this invention. The illustrations of FIGURES 1 through 6 and 11 are also exemplary, although novel. Each of the forms of fabric shown in FIGURES 1, 3 and 5 is illustrated in the form of a bedspread fabric. However, the same character of loop formation may be embodied in other terry fabrics, such as towels and the like, wherein relatively few yarns (usually three to six) are provided between adjacent loops both weftwise and warpwise of the fabric.

The fabric of FIGURE 1 includes a base F3 which may be woven from relatively fine or small warp and weft yarns as compared to the yarns employed in forming terry loops. The base F3 may be in the form of a plain or fancy weave, as desired. In this instance, the base F3 is provided with spaced weftwise extending relatively heavy yarns 86 preferably inserted immediately prior to each fast pick and up to fifteen or more picks apart. Thus, the rows of loops are spaced apart both warpwise and weftwise of the base, and the number of ground warps between adjacent rows of loops is sufficient so that the base F3 is readily visible between adjacent warpwise rows of terry loops and contrasts therewith to produce the desired pattern effect in the fabric. The loops are also shown spaced apart in a similar manner in FIGURES 3, 4, 5, 6 and 11.

It should be noted that the warpwise distance between adjacent weftwise rows of terry loops in FIGURES 1, 3 and 5 is substantially equal to or greater than the weftwise distance between adjacent warpwise rows of terry loops, and the weftwise distance between adjacent warpwise rows of terry loops is equal to or greater than at least three-fourths of the height of the longest loops in each row.

One purpose of the illustration of FIGURE 1 is to show how loops of different colored or textured yarns may alternate in hiding portions of other different textured or colored yarns. In weaving the fabric of FIGURE 1, it may be assumed that the terry warp T comprises one color or texture of relatively large terry warps alternating with another color or texture of large terry warps. The strands in the sheets S, S', S'' are also indicated by these same reference characters in FIGURE 1.

The warpwise rows of terry loops are generally designated at T10 through T14 in FIGURE 1. Weftwise rows are generally designated at W1 through W6. In weaving the loops in weftwise row W1, slackening bar 31 (FIGURE 10) remains stationary so that all loops are of a given height or length.

In forming loops in weftwise row W2 (FIGURES 1 and 2) as terry warps T are fed by overfeeding rolls 21, 22, slackening bar 31 moves forwardly in FIGURE 10 against sheet S to draw substantially all of the slack out of these strands while moving away from sheet S'. Thus, the subsequent fast pick beat-up stroke of reed 16 forms relatively short or ground-engaging loops from all the terry warps in sheet S (warpwise rows T10, T12, 14) while forming relatively high or long loops from all the terry warps in sheet S', and while forming loops of intermediate height of all the terry warps in sheet S'' (warpwise rows T11, T13).

It is thus seen that relatively short or ground-engaging loops of one color of terry warp in weftwise row W2 and warpwise rows T10, T12, T14 are concealed or hidden by the relatively high loops of the immediately adjacent strand. The intermediate loops formed of terry warps in sheet S'' in weftwise row W2 present loops of both colors with equal intensity.

In the weaving of the next succeeding weftwise row of loops W3, slackening bar 31 again remains stationary so that all loops are of the same height. On the other hand, in weaving weftwise row W4, slackening bar 31

moves rearwardly as terry warps T are fed by feed rolls 21, 22, so that additional slack is formed in sheet S while substantial slack is removed from sheet S'. Thus, with the next fast pick beat-up stroke of reed 16, the loops formed from strands in sheet S of FIGURE 1 are relatively high, the loops formed from strands S' are relatively low or ground-engaging loops, and the loops formed from strands S'' are all of intermediate height. This completes a cycle in the forming of the fabric shown in FIGURE 1, it being noted that weftwise rows W5 and W6 are identical to respective rows W1, W2.

The fabric of FIGURES 3 and 4 illustrates another arrangement of loops in which all the terry warps may be of the same or different colors and/or textures. Weftwise rows of loops W7 through W15 and warpwise rows of loops T15 through T23 are included, in FIGURE 3, with a base fabric F4. All the loops in warpwise rows T15, T21, T22, T23 may be of the same, intermediate, height or length and are, accordingly, formed from strands in sheet S'' of FIGURE 10, for example. The loops in warpwise rows T16, T18, T20, may be formed from strands in sheet S, while the loops in intervening warpwise rows T17 and T19 may be formed from strands in sheet S'.

It will be noted that, in weaving the first two weftwise rows W7, W8 in FIGURE 3, slackening bar 31 may remain stationary. In weaving the remaining weftwise rows W9 through W15, slackening bar 31 moves to and fro, in the manner heretofore described, to form high and ground-engaging loops in alternation, but in opposed relationship, from respective transpositional terry strands S, S'. The relative size of loops in FIGURE 3 is further illustrated in FIGURE 4.

The fabric of FIGURES 5 and 6 is also constructed in much the same manner as the fabrics of FIGURES 1 and 3, with the exception that the shedding of the ground warps is such that loops are formed on both faces of the base fabric F5, as heretofore described with respect to FIGURES 8 and 9. The base fabric F5 carries weftwise rows of loops W16 through W21 and warpwise rows of loops T24 through T31. Each warpwise row of loops T24 through T31 is formed from two terry warps.

All the loops in warpwise rows T25, T27, T29, T31 are of intermediate or medium length, although they appear on opposed faces of the base fabric F5 in alternation. Accordingly, these particular loops are formed from strands in sheet S'' of FIGURE 10 and, thus, bear the same reference character. The high loops in warpwise rows T24, T28 all appear on the back or lower face of the base fabric F5, but these loops may alternate with short or ground-engaging loops on the top of the base fabric F5 as will be presently described with respect to the loops formed from terry warps S in warpwise rows T26 and T30.

In the latter rows T26, T30, it will be noted that alternate loops made from one of the strands are, in each instance, relatively high loops and corresponding intervening loops made from the other of the strands are also relatively high loops. However, each of the strands alternates in the forming of high and low loops.

Very pleasing effects are also produced by forming alternate high and low loops from selected terry warps and wherein portions of the fabric would have the high loops formed on only one side thereof while the low loops are formed on the other side thereof, as heretofore described with respect to the fabric 80 in FIGURE 9. As heretofore stated, with respect to the fabric shown in FIGURE 7, all loops may vary as to length, although some immediately adjacent loops may be alternating high and low relative to each other.

Referring to FIGURE 11, a portion of terry fabric 90 is shown which is woven according to the present invention. However, the fabric 90 includes relatively short loops 91 alternating with tufts 92, both warpwise and weftwise of a base F6. These piles 91, 92 are

formed from terry warps interwoven with the base F6. Fabric 90 may originally be formed in the manner of any of the fabrics heretofore described and is shown only to illustrate the fabric after relatively high loops have been severed or sheared.

In the drawings and specification there have been set forth preferred embodiments of the invention and, although specific terms are employed, they are used in a generic and descriptive sense only and not for purposes of limitation, the scope of the invention being defined in the claims.

I claim:

1. A woven terry fabric comprising a base having a plurality of warpwise rows of loops formed of respective terry warps, the loops in each of certain selected rows being of varying heights with relatively high and relatively low loops being disposed in alternating sequence, the relatively high and relatively low loops in at least one row being in the weftwise planes of respective relatively low and relatively high loops in at least one other of said selected rows, some of said loops projecting from one face of the base, and others of said loops projecting from the other face of said base.

2. A terry fabric according to claim 1 including other warpwise rows of loops of substantially uniform height throughout at least a substantial portion thereof.

3. A woven terry fabric comprising a woven base, terry warps forming a plurality of warpwise rows of loops projecting from opposite faces of said base, certain of said rows each including alternating long and short loops, certain others of said rows each including alternating short and long loops in which the short and long loops of said certain other warpwise rows are disposed in the same weftwise planes as respective long and short loops of the first-mentioned certain warpwise rows whereby intersecting weftwise and warpwise rows of loops of at least two different lengths project from the base fabric, all the long loops in certain substantial portions of at least some of said rows protruding from one face of said base, and all the short loops in said certain portions of said some of the rows protruding from the opposite face of said base.

4. A woven terry fabric comprising at least one warpwise row of alternating high and low pile loops formed from a single strand of terry warp, at least one other warpwise row of high and low pile loops also formed from a single strand of terry warp, the high and low loops in the first-mentioned row being disposed in the same weftwise plane as the respective low and high loops of the other warpwise row, each of said warpwise rows of pile loops including at least one loop of another given height disposed warpwise between certain adjacent pairs of high and low loops, at least some of the loops in said one warpwise row projecting from one face of the fabric and at least some of the loops in said other warpwise row projecting from the opposite face of the fabric.

5. A woven terry fabric comprising a base, terry warps forming a plurality of warpwise rows of loops projecting from said base, certain of said rows each including alternating high and low loops, certain others of said rows each including alternating low and high loops in which the low and high loops of said certain other warpwise rows are disposed in the same weftwise planes as the respective high and low loops of the first-mentioned certain warpwise rows, whereby intersecting weftwise and warpwise rows of loops of at least two different lengths project from the base, all of said warpwise rows of loops also including some loops of uniform height which form weftwise rows of uniform-height loops, at least some of said loops projecting from one face of the base, and others of said loops projecting from the opposite face of the base.

6. A woven terry fabric comprising a base of interwoven warps and wefts, first and second terry warps in-

terwoven with said base in the form of warpwise rows of alternating high and low piles, the high piles formed of said first terry warps being in weftwise alignment with the low piles formed of said second terry warps and vice versa, some of said piles projecting from one face of said base, and others of said piles projecting from the other face of said base to form a pattern.

7. A woven terry fabric comprising a base having a plurality of warpwise rows of terry pile loops, each warpwise row including loops of at least two different heights interwoven with said base, said warpwise rows of loops also forming weftwise rows of loops wherein the loops of each weftwise row are of at least two different heights, some of the loops in certain warpwise rows projecting from one face of the base, and other loops in said certain rows projecting from the other face of the base.

8. A woven terry fabric comprising a base having a plurality of warpwise rows of terry pile loops, each warpwise row including loops of at least two different heights interwoven with said base, said warpwise rows of loops also forming weftwise rows of loops wherein the loops of each weftwise row are of at least two different heights, each of said warpwise rows including relatively long and relatively short loops, relatively long loops in portions of said rows projecting from one face of the base, and relatively short loops in said portions of said rows projecting from the other face of said base.

9. A woven terry fabric having a plurality of warpwise rows of loops, each row including loops of at least three different lengths, said warpwise rows of loops also forming weftwise rows of loops, each weftwise row including loops of at least two different lengths, said loops projecting from opposite faces of the fabric, and the loops of one length, when taken with the loops of another length on the same face of the fabric, forming a pattern in relief on said same face.

10. A woven terry fabric comprising a woven base, at least one first warpwise row of alternating high and low pile loops formed from a single strand of terry warp interwoven with said base, at least one other warpwise row of high and low pile loops also formed from a single strand of terry warp interwoven with said base, the high and low loops in said first row being disposed in the same weftwise planes as respective low and high loops of the other warpwise row, a plurality of adjacent high loops in portions of said rows projecting from one face of the base, and the low loops in said portions projecting from the other face of said base.

11. A woven terry fabric comprising a woven base, a first plurality of spaced terry warps alternately arranged with respect to a second plurality of terry warps, said first and second terry warps forming respective first and second warpwise rows of loops projecting from said base, said first rows including alternating long and short loops, said second rows including alternating short and long loops in which the short and long loops of said second warpwise rows are disposed in the same weftwise planes as respective long and short loops of the first warpwise rows whereby intersecting weftwise and warpwise rows of loops each of at least two different lengths project from the base fabric, embossed effect areas formed only by the long loops projecting from one face of the fabric in adjacent portions of some of said first and second warpwise rows, portions of the fabric surrounding said areas being formed only with corresponding short loops projecting from said one face in said some of said rows and in other rows adjacent said some of the rows, and recessed effect areas being formed on the opposite face of the fabric, said recessed effect areas coinciding with said embossed effect areas and being formed with corresponding short loops projecting from said opposite face of the fabric in said portions of some of said rows, and wherein those portions of the fabric surrounding said recessed effect areas are formed only with corresponding

long loops projecting from said opposite face in said some of the rows and in said other rows adjacent said some of the rows.

12. A woven terry fabric comprising a base of interwoven ground warps and wefts, a plurality of first and second relatively large continuous terry warps interwoven with said base each in the form of warpwise rows of alternately arranged warpwise spaced relatively long loops with relatively short loops spaced between adjacent long loops, certain of said long loops of the first terry warps being in weftwise alinement with certain of said short loops of the second terry warps and certain of said long loops of the second terry warps being in weftwise alinement with certain of said short loops of said first terry warps, a plurality of said ground warps being positioned between adjacent terry warps through the length of the fabric, said plurality of ground warps being sufficient in number so that a substantial portion of the base is readily visible between adjacent warpwise rows of terry loops and contrasts therewith to produce the desired pattern effect, and adjacent long and short loops being spaced apart warpwise a distance substantially equal to the weftwise distance between adjacent terry warps.

13. A terry fabric according to claim 12 wherein some of the loops project from one face of the base and other loops project from the other face of the base.

14. A woven terry fabric comprising a base of interwoven ground warps and wefts, a plurality of first and second continuous terry warps interwoven with said base each in the form of warpwise rows of warpwise spaced relatively long loops interspersed with short ground-engaging loops, certain of said long loops of the first terry warps being in weftwise alinement with certain of said ground-engaging loops of the second terry warps and certain of said long loops of the second terry warps

20 25 30 35

being in weftwise alinement with certain of said short loops of said first terry warps, a plurality of said ground warps being positioned between adjacent terry warps throughout the length of the fabric, said plurality of ground warps being sufficient in number so that adjacent warpwise rows of terry loops are spaced apart a distance at least equal to three-fourths the length of said long loops and so that the base is readily visible between adjacent warpwise rows of terry loops and contrasts therewith to produce the desired pattern effect, and warpwise adjacent loops being spaced apart a distance at least equal to the distance between adjacent warpwise extending rows of terry loops.

15. A terry fabric according to claim 14 wherein some of the loops project from one face of the base and other loops project from the other face of the base.
